UNITED STATES PATENT OFFICE.

COLONEL C. HEETER, OF BUTLER, PENNSYLVANIA.

WELL-PACKER.

No. 904,202.

Specification of Letters Patent.

Patented Nov. 17, 1908.

Application filed January 25, 1907, Serial No. 354,046. Renewed April 7, 1908. Serial No. 425,705.

To all whom it may concern:

Be it known that I, COLONEL C. HEETER, a citizen of the United States, residing at Butler, in the county of Butler and State of Pennsylvania, have invented certain new and useful Improvements in Well-Packers, of which the following is a specification, reference being had therein to the accompanying drawing.

10 This invention relates to that class of well-packers wherein an anchorage on the well wall operates in conjunction with an abutment through which the packer-tube is movable for expanding the packer, and the primary object is to provide improved means for setting the anchor.

A further purpose is to provide a yielding support for the anchor which may give while the anchor is being set and prevent injury thereto in the event of excessive strains or pressure.

In the accompanying drawing, Figure 1 is a view, partly in elevation and partly in section, of the improved packer, showing the position of the parts while being lowered in a well. Fig. 2 is a longitudinally sectional view, showing the position of the parts while setting the anchor, and Fig. 3 is a similar view of the packer when set.

30 Referring to the drawing, 2 designates the packer-tube or body having at its upper end the usual collar 3 for uniting with casing 4, and beneath the collar is the packer or rubber annulus 5. Loose on tube 2, at the lower end of annulus 5, is a two-part abutment consisting of inner sleeve 6, against which the packer bears and which fits within an outer sleeve 7, being connected thereto by coarse threads 8. Tube 2 may be formed 40 with one or more longitudinal slots 9 to receive pins 10 projecting from sleeve 6, whereby, while said parts are held against independent rotation, the tube is free to move longitudinally within the sleeve. Springs 45 45 carried by outer sleeve 7 impinge the well-wall and prevent said tube from rotating. A shoulder 12, at the upper end of sleeve 7 engages pin 12' projecting from sleeve 6, thereby preventing the sleeves from becoming screwed together so tightly as to resist separation when setting the packer in manner presently to be described. A collar 13 carried by the lower end of tube 2 forms a stop for spring 14, and resting on the latter is the 50 annular slip-carrier 15 loose on the tube. Projecting upward from the carrier are

spring-arms 16, each having a wedge shaped slip-head 17, the spring-arms operating to hold the slips normally contracted, as shown in Fig. 1.

60 In operation, the packer is lowered in the well to the desired point, and is then rotated by turning casing 4. As sleeve 7 is prevented from rotating by springs 11, the rotary movement results in the distention of 65 the thread-connected two-part abutment, as shown in Fig. 2, the immediate result being the forcing downward of sleeve 7, thereby engaging the tapered lower end 7' thereof with slips 17, and forcing the latter outward 70 into tight contact with the wall. If this expanding movement is carried too far, or if the rock-wall is extremely hard and unyielding, spring 14 permits the slips to move downward slightly under the excessive pressure, thereby preventing the slips, sleeve 7 or 75 other parts of the packer from being injured by the undue strain. After the packer has been set in the manner described, and as shown in Fig. 2, the support for the casing 80 at the top of the well is removed, and the weight of the casing forces tube 2 downward, thereby compressing the rubber annulus between collar 3 and the anchored abutment and laterally expanding the packer and sealing the well, as shown in Fig. 3. The packer 85 may be released by rotating the same through the medium of the casing in direction reverse to that in which it was turned when being set, thereby contracting the two-part abutment by drawing upward sleeve 7 and releasing slips 17. The casing and tube 90 2 are then drawn upward, permitting the rubber to resume its normal shape, with the entire device free to be either raised or lowered, when it may be reset at a different point by repeating the above described setting operation, or removed from the well. 95

I claim:

1. The combination of a tube, an expandable packer thereon, a longitudinally extensible abutment for the lower end of the packer and through which the tube is adapted to move, and an anchor beneath the abutment and adapted to be engaged and set by the latter while being longitudinally extended.

2. The combination of a tube, an expandable packer thereon, a longitudinally extensible two-part abutment for the lower end of the packer through which the tube is movable, the abutment parts fitting one within

the other and united by screw-threads, holding means adapted to prevent the outer abutment part from rotating, and an anchor adapted to be engaged and set by said outer part when the abutment is extended longitudinally by rotating its inner part.

3. The combination of a tube, an expandible packer thereon, a longitudinally extensible two-part abutment, said parts fitting 10 one within the other and united by screw-threads, a longitudinally movable connection between the tube and the inner part of the abutment adapted to prevent the tube and said part from turning independently of 15 each other, wall-engaging springs carried by the outer abutment-part for preventing rotation of the latter, and an anchor adapted to be engaged and set by said outer part when the abutment is extended longitudinally by 20 rotating its inner part.

4. The combination of a tube, an expandible packer thereon, an abutment for the lower end of the packer through which the tube is movable, the abutment consisting of 25 two sleeves movable one within the other and

united by screw-threads, a pin and slot connection between the tube and inner sleeve to afford the tube longitudinal movement through the sleeve, the outer sleeve having its lower end tapered, means carried by the outer sleeve for resisting rotation, and wedge-shaped slips movable on the tube and adapted to be engaged and expanded by the tapered lower end of the outer sleeve.

5. The combination of a tube, an expandible packer thereon, two sleeves—one within and threaded to the other—through which the tube is movable, a connection between the tube and inner sleeve for causing said parts to turn together, holding means for preventing turning of the outer sleeve, stop means for preventing the sleeves from tightly screwing together, and an anchor adapted to be set by the outer sleeve.

In testimony whereof I affix my signature 45 in presence of two witnesses.

COLONEL C. HEETER.
